ness Machines Corp., New York, N. Y., a cor-
poration of New York

Application March 24, 1938, Serial No. 197,943

4 Claims. (Cl. 234—36.5)

This invention relates to printing machines and more specifically to printing machines of the remote control type in which data is caused to be printed on a tape which is fed at the time of printing from electrical impulses initiated from a remote source.

It is well known that the traffic conditions both as to vehicular and pedestrian traffic has increased so rapidly that many problems have been presented. In the vehicular field particularly, the roads have been crowded to a point where large expenditures for building new roads to relieve others already built and to widen and improve all roads have been made. In order to determine at what points expenditures could be made to the greatest advantage, it has been the custom in the past to station observers at a fixed point along the highway to observe and count the passing traffic. To procure accurate figures this required a long and tedious vigil with no check up on the operator to make sure that he was attending strictly to duty. It is the purpose of the applicant's invention to provide a machine which, when connected to the proper control, will perform its operation automatically and unattended.

It is, therefore, an object of this invention to provide a printing device which will automatically print an account at predetermined intervals of time together with the time of day and the day of the week whereby successive counts will determine the number of objects recorded on the sheet for each hour of the day.

It is a further object of the invention to provide a printing device which is operated remotely by commercial current and which upon current failure will effect a printing operation immediately upon the resumption of the power supply and thereafter at the regular stated time intervals, thereby giving indication of such current failure by the lack of continuity of the record and the time differential as shown by the last timed record on the sheet and the time of day at which the operator removes the sheet.

Further objects of the instant invention reside in any novel feature of construction or operation or novel combination of parts present in the embodiment of the invention described and shown in the accompanying drawings whether within or without the scope of the appended claims and irrespective of other specific statements as to the scope of the invention contained herein.

In the drawings:

Fig. 1 shows a front elevation of the device;
Fig. 2 shows a side elevation;

Fig. 3 shows a detail portion of the timed mechanism;

Fig. 4 shows a detail view of the counting mechanism;

Fig. 5 is a detail view of the ribbon mechanism;

Fig. 6 is a wiring diagram of the machine; and
Fig. 7 shows a section of the tape.

The machine in general is mounted on a supporting plate 11 at the back with studs 12 10 mounted thereon and projecting forward to support other suitable plates for journaling rotating parts and supporting numerous sub-assembly supporting brackets.

15

Timing mechanism

The timing mechanism is provided with a synchronous motor 13 having a series of reduction gears not shown but enclosed in a housing 14 which is mounted on a supporting plate 11. Such 20 motors and reduction gears are well known in the art as, for instance, that shown in the patent to H. E. Warren No. 1,495,936, dated May 27, 1924. A shaft 16 (Fig. 3) issues from the reduction gearing and passes through the support- 25 ing plate 11 to the front side of the plate, said shaft making one revolution per minute. Fixed to the shaft are cams 17 and 18. A cam wiper 19 cooperates with the cam 17 and is rotatably mounted on a shaft 20. The cam wiper is formed 30 in a U-shaped member having one leg portion 18 and the other leg shown at 21. This cam wiper is urged in a counterclockwise direction by a spring 22 anchored to the bracket 23. An extension 24 integral with the leg 21 cooperates with 35 a notched wheel 26 to prevent overthrow when the cam wiper 19 is dropped from the point of the cam. The pawl 27 is pivotally mounted on the member 21 and urged in a clockwise direction by a spring 28 and also cooperates with the 40 notches in the wheel 26. A retaining pawl 29 is pivotally mounted at 30 and urged in a clockwise direction by a spring 31. As the cam 18 turns in a clockwise direction, the cam wiper 19 is raised and the projection 24 disengaged 45 from the notches and the pawl 27 is retracted along the edge of the wheel when the cam wiper drops from the high point. The power in the spring 22 causes the pawl 27 which is engaged in one of the notches to move the wheel 26 in a 50 clockwise direction. This wheel is moved $\frac{1}{60}$ of a revolution for each drop of the cam wiper 19, thus causing the wheel 26 to make one complete revolution in an hour.

The wheel 26 is rotatably mounted on a bush- 55

ing 35 and has a minute type wheel 44 fixed to it so that it makes one revolution per hour. The type wheel has type characters on its periphery for 00 to 59 representing minutes. A cam 25 (Fig. 2) similar to the cam 33 is fixed to the wheel 26 on the opposite side from the type wheel. This cam therefore is located in back of the notched wheel 42 and in front of the wheel 26 as viewed in Fig. 3.

13 The end of a cam wiper 35 rides on the cam 25 fixed to the minute wheel 26 which will hereafter be called the minute wheel cam. The cam wiper is fixed to a bushing rotatably mounted on shaft 36. A pawl carrier 40 is also fixed to the same bushing and the cam wiper 35 is provided with a projection 50 integral therewith, so that the cam wiper, its projection and the pawl carrier move in unison. The minute wheel cam is a one step cam and, as the wheel 26 makes 20 one revolution per hour, the pawl arm 40 will be raised and dropped once per hour. Pivoted mounted at one end of the pawl carrier 40 is a pawl 41 which engages the notches of the wheel 42. A retaining pawl 43 which is pivoted on a shaft 30 engages the notches in the wheel 42 to hold it against counterclockwise rotation. When the pawl carrier 40 is raised to allow the pawl 41 to engage the notch above the end of the pawl carrier, such as indicated at 45, and then dropped, the angular end of the pawl strikes the pin 46 fixed in the end of the retaining pawl and disengages it from the notch of the wheel 42, to permit the wheel to be advanced an angular distance of one notch each time the pawl 41 is raised and dropped. There are 24 notches in the wheel 42 representing the twenty-four hours in the day, so that the wheel 42 will make one rotation a day. The wheel 42 is fixed to the bushing 35 which is rotatably mounted on the shaft 32 and an hour type wheel 46 (Fig. 2) is fixed to the other end of said bushing, so that it makes one revolution per day as does the wheel 42.

Said type wheel carries type characters designating the hours of the day.

45 The cam 33 is fixed to the wheel 42 and engages a cam wiper 34 which is pivotally mounted on the shaft 36. A member 38 having a projection 39 offset to lie in the plane of the cam wiper 34 is fixed to the shaft 36. The projection 39 abuts the under side of cam wiper 34 and is held in contact by means of the spring 37; at the opposite end of the shaft 36 is type wheel actuating mechanism of exactly the same type as those just described with a pawl, similar to pawl 41, engaging a notched wheel 47 (Fig. 2) which is 50 fixed to the day type wheel 55. As the cam wiper 34 is raised and lowered once a day, it carries the member 38 which oscillates the shaft 36 to raise and lower the pawl cooperating with the notched wheel 47 to advance it one tooth. There are 14 55 notches on the wheel 47, so that it makes a complete cycle every two weeks and the day type wheel has 14 day characters representing the days of the week repeated twice. The type actuating mechanism and transfer mechanism just described are old in the art and are shown in more detail in U. S. Patent No. 552,232 (Fig. 12) and in U. S. Patent No. 671,126 (Fig. 10).

Cam wipers 48 cooperate with a cam 18 to close 70 the contact fingers 49 once each minute for a duration of about two seconds. These contacts are designed to close on the exact 60th second of the minute. Such contacts are old and fully described in the patent to C. E. Larrabee, No. 75 1,878,931, and are shown in Fig. 2 of that patent

as operating contact 28 in that figure. Fixed to the arm 40 is an extension 50 which is pivotally connected to a link 51 of a toggle, the other link of which is shown at 52 and is pivotally attached to a contact block 53 pivoted at 54 to the supporting plate 56. The contact block is biased in a clockwise direction by a spring 57 and has mounted thereto and insulated therefrom a contact 58. As the cam wiper 34 is raised by the cam 33, the projection 50 rotates in a counter-clockwise direction and the links 51 and 52 straighten out to form a straight line between their extreme pivot points on the projection 50 and contact block 53. When the cam wiper 34 drops from the high point of the cam, the projection 50 rotates in a clockwise direction causing the contact block 53 to also rotate counter-clockwise so that the contact 58 closes with the contact 59 which is mounted on the bracket 23 but insulated therefrom. A limit stop 60 limits the rotation of the contact block 53 in a clockwise direction. A bell crank 61 is pivoted on the shaft 36 and extends behind the lever 40 with an upwardly turned projection 62 and has a turned over end 63 which lies in the plane of the toggle 51, 52. For reasons to be explained later, the minute the contacts 58 and 59 close, the bell crank 61 is rotated counterclockwise so that the turned over portion 63 strikes the projection 64 of the toggle which has been moved to the right from the position shown in Fig. 3, due to the dropping of the cam wiper 34. When the projection 64 is struck, the straight line of the toggle is broken and the spring 57 immediately opens the contacts 58, 59. The bell crank 61 is pivotally connected to a lever 66 and is operated thereby in a manner to be described later.

Counting mechanism

To the supporting plate 67 which is mounted on the studs 12 is mounted a magnet assembly 68 including a magnet 69 having a solenoid plunger 70 reciprocably mounted in its core (Fig. 2). The plunger is provided with a slot 71 at its lower end having the pin 72 (Fig. 4) which engages a slot in one arm 73 of a U-shaped member 74 which is pivotally mounted on a stud 76. The other arm 77 has an off-set portion 78 which runs parallel with the shaft 79 and supports at its outer end an insulating block 80 which lies in the plane of the lower blade of the normally open contacts 81. Two pawls 82, 83 are pivotally mounted on the arm 77 of the U-shaped member and cooperate with the ratchet wheel 84. The pawls are urged into cooperation with said ratchet wheel by means of springs 86, 87. When the solenoid 70 is lifted by energization of the magnet 69, the ratchet wheel 84 is rotated in a clockwise direction a distance of half a tooth. The pawl 83 retrogresses a half tooth as the ratchet wheel moves forward so that it engages the next successive tooth so that, upon deenergization of the magnet 69, the solenoid plunger drops and the pawl 83 moves the ratchet wheel for the remaining half of the tooth arc 85 with a result that the ratchet wheel moves a distance of one tooth with each up and down movement of the plunger. A spring 88 attached to an extension 89 of the U-shaped member 74 biases the same in a counterclockwise direction. A 70 units type wheel 90 is fixed to the ratchet wheel 84 having units one to zero thereon and the type wheel has ten teeth so that each advance of the ratchet wheel for one tooth turns up a succeeding number in the units type wheel. 75

Transfer from the units to the tens and from the tens to the hundreds is accomplished by the usual well known Geneva type of transfer. The type wheels as a group are generally shown at 91 in Fig. 2.

Printing mechanism

A magnet assembly generally shown at 92 is mounted to its supporting plate 11 and includes a magnet 93 having a hollow core inside of which is a solenoid plunger 94. An anvil 96 having a projection 97 extending into the core of the magnet rests on the upper end of the magnet assembly and is provided with a platen 98. When the magnet 93 is energized, the plunger 94 is drawn up into the coils striking the projection of the anvil 96 and throwing the platen against the type wheels.

A ribbon 99 and a record strip 100 pass between the type wheels and the platen with the ribbon adjacent the type wheels and the record strip adjacent the platen, so that when the platen is projected against the type wheels a printing of the type is effected on the paper strip. A pin 101 is fixed to the plunger 94 and engages the lower edge of the lever 102 which is pivotally mounted at 103. When the magnet 93 is energized and the plunger 94 is propelled upwards, the engagement of the lever 102 with the pin 101 causes the lever to be rotated counterclockwise as viewed in Fig. 1. The lever 102 is normally biased in a clockwise direction by a spring 104 and is provided with a hook-shaped end 106 (Fig. 5) which engages the end 107 of a lever 108 which is pivotally mounted on the shaft 109 and which is biased in a clockwise direction by a spring 110. A pawl 111 is pivotally mounted to the lever 108 and held in engagement with a ratchet lever 112 by a spring 113. As the lever 102 rocks in a counterclockwise direction, the hooked end 106 is raised and the lever 108 is rotated clockwise by spring 110 so that the pawl is rotated to pick up two teeth of the ratchet wheel 112 and upon the return downward of the hooked end 106, the ratchet wheel is rotated in a counterclockwise direction. The ratchet wheel 112 is fixed to the shaft 109 which carries a receiving spool 114 which is splined to the shaft to rotate with it. The receiving spool has one end of the paper strip 100 fastened thereto which is wound onto the spool as the paper is fed by means of the turning of the ratchet 112. The paper is supplied from a supply roll 116 which is pivotally mounted on a stud 117. The shaft 109 is journaled in the plate 11 and extends to the bracket 118 which together provide a cantilever support for the other end of the shaft on which the receiving spool is mounted. The ribbon 99 is a continuous ribbon, and is carried over spools 119 which are rotated and mounted on pins over an ink supplying roll 120 which is made of suitable absorbent material to carry a supply around a take-up spool 121. The take-up spool is mounted on a lever 122 pivoted at 123 and biased in a clockwise direction by a spring 124. This spool is for the purpose of taking up the slack in the ribbon and creating a typical pressure and friction drive between the ribbon and the supply roll 120. The ribbon is fed at the same time that the paper strip is fed by means of the gear 126 fixed to the shaft 109 and meshing with a gear 127 which is fixed to the ink supply roll 120, both of which are rotatably mounted on the stud 128.

75 It will be noted that the feeding of the paper

strip and the ribbon is effected after printing upon the downward movement of this solenoid plunger 94.

Pivots mounted to the left end of the lever 102 as viewed in Fig. 5 is the link 86 previously referred to. This link has a pin 129 mounted thereon and extending into the path of the blades of contact 130 (Fig. 3). As the lever 102 is rocked counterclockwise when printing is effected, the link 86 is drawn downwardly rocking the bell crank 81 counterclockwise to cause the off-set end of the bell crank 83 to break the toggle 51, 52 as previously explained. When printing is effected, a number shown on the counter and the day and time are printed on the strip in alignment as shown in Fig. 6.

The operation of the machine will now be described.

The terminal posts 131 may be connected with any type of control system that may be effected by the passing of traffic which will send one electrical impulse to the magnet 132 each time a unit passes. Such a control system may be of the well-known type of contact mechanism placed in the ground for the wheels to run over as is used in connection with traffic lights or it may be a light sensitive cell operated control device having a light beam thrown across the path of the traffic. For the purposes of describing the operation of the recording device, it will be assumed that the operation is controlled by the latter type such as that shown in the patent to W. D. Cockrell, No. 1,995,881, dated March 26, 1935. Although this control device is shown in operation of counting persons passing through the beam, it may be well understood that the beams could be thrown across the roadway to be intercepted by the passing of automobiles. With such a control device being used, the circuit that is run to the counter 14 as shown in the Cockrell patent would be in this instance connected to the terminal posts 131 shown in the applicant's device whereby electrical impulses would be received by the magnet 132 each time an automobile or other vehicle cut the light beams. Such impulses would energize the magnet 132 of a relay causing the relay contacts 133 to close. A source of commercial power supply would be connected to the terminals 134 and 136. With the closing of the contacts 133, current will then flow through the line 137, contacts 133 now closed, counter magnet 69, normally closed, relay contacts 138, wires 139, 140, 141 causing the counter magnet to be energized and rotating the type wheel 90 in the manner previously explained.

In the event that a vehicle should stop in the path of the light beams, the relay magnet 132 would remain energized. In order to prevent the counter magnet 69 from being held up, a circuit is provided from the terminal 136 through line 137, relay contact 133, relay coil 142, line 143, counter-operated contacts 81, lines 144, 139, 140, and 141 to the terminal 134. As previously explained, when the counter magnet 69 is energized, the contacts 81 close. The closure of these contacts in the circuit just described, energizes relay magnet 142 and causes the normally closed contacts 138 to open thereby breaking the circuit to the counter magnet 69 and causes relay contacts 146 to close, thereby establishing a stick circuit through the relay magnet 142 as follows: From the terminal 136, through line 137, relay contacts 133, relay magnet 142 and its contact 146 now closed, lines 139, 140, and 141 to the ter-

rninal 134. The relay magnet 142 therefore will remain energized as long as the light beams remain broken.

The motor 13 is connected across the terminals, 5 134 and 136 and runs constantly while the power supply is available. The minute contacts 49 are controlled by the cam 18 and are connected in series with the hour contacts 58 and 59 which are controlled by the cam 17. In order to simplify 10 the diagram, these contacts are diagrammatically shown in Fig. 7 as being directly controlled by the cam instead of through the linkages as explained in connection with Fig. 3.

The adjustment of the hour contacts and their 15 associated cam is such as to cause the contact to close within the range of plus or minus thirty seconds of the hour, so that these contacts will be closed when the minute contact 49 closes on the sixtieth second of the sixtieth minute of the 20 hour. The closure of these two sets of contacts in series will energize the print magnet 93 to effect a printing operation by the following circuit: From terminal 134, line 141, minute contacts 49, hour contacts 58 and 59, print magnet 93, line 147 25 to the terminal 136. A relay consisting of a relay magnet 148 and relay contacts 149 and 150 is normally held in an energized position with the relay magnet 148 energized so that the relay contacts 149 are normally held in closed position to 30 close a holding circuit for this magnet as follows: From terminal 134 to lines 141, 140, 151, relay magnet 148, relay contacts 149, lines 152 and 147 to the terminal 136. It will be recalled that the link 66 carrying a pin 129 closes the contacts 130 35 each time the print magnet is energized. In the event that there is an interruption in the power supply, means are provided to effect a printing operation immediately upon the resumption of said power supply regardless of the time after 40 which the regular timed cycle of printing is effected. This is accomplished as follows: When the power supply is interrupted, relay magnet 148 becomes deenergized opening its contacts 149 and closing the contacts 150. Immediately upon 45 the resumption of the power cycle, current passes through the magnet 93 to energize the same and effect a printing operation through the following circuit: From terminal 136, through line 147, printing magnet 93, line 153, relay contacts 150 50 now closed, line 151, 140, and 141 to terminal 134. With the operation of the printing magnet, contacts 130 are closed completing a circuit through 55 the relay magnet 148 as follows: Terminal 136, line 147, contacts 130, line 154, relay magnet 148, lines 151, 140, and 141 to the terminal 134. The energization of the magnet 148 opens contacts 150 to break the circuit through the printing magnet and closes contacts 149 to again form a holding circuit for the magnet 148 to hold it in energized position. The printing magnet then 60 functions at the regular timed interval as previously described. It will be seen therefore that with resumption of power after a power failure that the print made will show the time at which the power failed. For example, the last print made as 65 shown in Fig. 7 is 4:15 which shows a power failure at that time. The next impression thereafter will occur on the even hour at 5:00 o'clock machine time, and the observer who collects the records may note the discrepancy between the time 70 indicated by the machine when he makes his observation and his watch to determine the amount of time that the power was off. The attendant, of course, is always instructed to take 75 such a record and correct the time in case there

has been such an interruption of the current. The underscoring under the hour figure represents P. M.; no underscoring is made for A. M. This is in accordance with the usual custom, old in the art.

While there have been shown and described and pointed out the fundamental novel features of the invention as applied to a single modification, it will be understood that various omissions and substitutions and changes in the form and details 10 of the device illustrated and in its operation may be made by those skilled in the art without departing from the spirit of the invention. It is the intention, therefore, to be limited only as indicated by the scope of the following claims.

What is claimed is:

1. A record printing machine operatively connected to a source of power supply including type wheels having time recording characters thereon, a platen associated therewith, said type wheels and platen being movable relative to each other to effect a printing operation, electromagnetic means for effecting relative motion between said type wheels and platen, cyclically operated means for controlling the operation of said electromagnetic means, a circuit connecting the power supply source with said cyclically operated means and extending to said electromagnetic means and means, normally held in one position by said power supply, interposed in said circuit between 20 said cyclically operated means and said electromagnetic means to hold the circuit closed between them, said means being moved to an alternate position upon failure of said power supply to open said circuit and to connect said electromagnetic means directly to said power supply whereby said electromagnetic means will be operated upon the termination of said power failure to effect a printing operation.

2. A record printing machine operatively connected to a source of power supply including relatively movable type wheels and platen for effecting printing, electromagnetic means for controlling the relative movement between said type wheels and platen, cyclically operated means 40 for controlling the operation of said electromagnetic means, a circuit connecting the power supply source with said cyclically operated means and extending to said electromagnetic means, means, normally held in one position by said power supply, interposed in said circuit between 45 said cyclically operated means and extending to said electromagnetic means to hold the circuit closed between them, said contacts being moved to an alternate position upon failure of said power supply to open said circuit and to connect said electromagnetic means directly to said power supply whereby said electromagnetic means is 50 operated upon the termination of said power failure to effect a printing operation, and means 55 controlled by the operation, of said electromagnetic means for causing said last named means to be restored from its alternate position to its normal position whereby the control of the operation of said electromagnetic means by said cyclically operated means is resumed.

3. A record printing machine operatively connected to a source of power supply including type wheels having time recording characters thereon, a platen associated therewith, said type wheels and platen being movable relative to each other to effect a printing operation, an electromagnetic device for effecting relative motion between said type wheels and platen, cyclically operated means for controlling the operation of 70

5 said electromagnetic device, a circuit connecting the power supply source with said cyclically operated means and extending to said electromagnetic device and means comprising a plurality of contacts normally held in one position by said power supply interposed in said circuit between said cyclically operated means and said electromagnetic device to hold the circuit closed between them, said contacts being moved to an alternate position upon failure of said power supply to open said circuit and to connect said electromagnetic device directly to said power supply whereby said electromagnetic device will be operated upon the termination of said power failure to effect a printing operation.

10 4. A record printing machine operatively connected to a source of power supply including relatively movable type wheels and a platen for effecting printing, an electromagnetic device for controlling the relative movement between said type wheels and platen, cyclically operated means for controlling the operation of said electromag-

5 netic device, a circuit connecting the power supply source with said cyclically operated means and extending to said electromagnetic device, means comprising a plurality of contacts normally held in one position by said power supply 10 interposed in said circuit between said cyclically operated means and said electromagnetic device to hold the circuit closed between them, said contacts being moved to an alternate position upon failure of said power supply to open said circuit 15 and to connect the electromagnetic device directly to the power supply so that said electromagnetic device is operated upon the termination of said power failure to effect a printing operation, and means controlled by the operation of said electromagnetic device for causing said contacts to be restored from the alternate position to the normal position whereby the control of the operation of said electromagnetic device by said cyclically operated means is resumed.
